THIMBLE OR FINGER PROTECTOR

Jeannette Lloyd, New York, N. Y.

Application September 13, 1945, Serial No. 616,040

10 Claims. (Cl. 223—101)

1

This invention relates to a thimble or finger protector particularly useful in knitting, crocheting or other similar operations to provide a bearing surface for thread and to maintain the same under tension.

In various operations, such as knitting and crocheting, it is customary to wrap two or three turns of the thread around the finger to assure proper tension on the thread. This maintaining of the thread under tension may result in irritation of the finger and possible breakage of the thread due to holding the latter too tight. Additionally, the drawing of the thread over the finger is physically uncomfortable.

It is therefore among the objects of this invention to provide a thimble formed with means for guiding thread or yarn; to provide such a thimble formed with a continuous thread or yarn guiding means on its external surface adapted to guide thread or yarn from one end of the thimble to the other and to maintain it under tension; to provide such a thimble including a shell having either a closed or open end and an external surface formed with thread or yarn guiding and tensioning means adapted to guide thread or yarn in several turns over such external surface; to provide such a thimble in which the guiding means is adaptable to threads or yarn of widely different diameters or thicknesses; to provide a thimble having a helical rib on its external surface for guiding and tensioning thread or yarn; to provide a thimble having a helical rib on its external surface and a helical groove adjacent the base of the rib, for guiding thread or yarn of widely differing diameters around the thimble from one end to the other thereof; and to provide a simple, and inexpensive device for guiding and tensioning thread or yarn during knitting or crocheting operations.

These and other objects, advantages and novel features of the invention will be apparent from the following description and the accompanying drawing.

In the drawing:

Fig. 1 is a somewhat schematic view illustrating the device of the invention as applied to the finger during a knitting or crocheting operation.

Fig. 2 is a perspective view of a thimble according to the present invention.

Fig. 3 is a longitudinal sectional view through the thimble of Fig. 2.

The present invention comprises a thimble including a finger fitting shell which may have either a closed or open outer end. The external

2

surface of the shell is provided with a continuous thread or yarn guiding and tensioning means, preferably including a helical rib. A helical groove is formed adjacent the helical rib and is preferably made very shallow. In cross-section, the helical rib is concavo-convex, with its concave surface on the side nearest the groove, so that an overhanging lip is provided adjacent the outer periphery of the rib. Threads or yarns of small diameter are guided and tensioned in the shallow helical groove, whereas larger diameter threads or yarns are guided and tensioned in the concavo-convex rib. The thread or yarn thus takes several turns around the thimble in passing from the supply to the point of use, and suitable tension is thus maintained thereon without undesirable friction on the skin of the finger.

Referring to Fig. 1 of the drawing, the thimble 10 of the invention is illustrated as applied to the index finger 11 of a left hand 13 to guide a thread or yarn 12 from a source of supply to the knitting or crocheting apparatus contained in the right hand. Fig. 1 is exemplary only, and illustrates the invention as applied to a crocheting operation. The invention is applicable with equal facility to knitting or other operations involving the use of a pair of needles, with one held in each hand. Thread 12 is guided around a helical guiding means generally indicated at 15 so that several turns are provided around thimble 10. While the helical guiding means is shown as having a "left-hand" thread, this is exemplary only, and a "right-hand" thread may be used with equal facility.

As shown in Figs. 2 and 3, thimble 10 comprises a shell 20 having a closed outer end 25. Shell 20 is somewhat frusto-conical in shape so as to fit the end of a finger. The external surface of shell 20 is provided with a continuous thread or yarn guiding and tensioning means. Such means comprises a helical rib 16 which is concavo-convex in cross section, having a convex outer surface 17 and a concave inner surface 18. Concave inner surface 18 thus provides an overhanging lip 21, for a purpose to be described hereinafter. Helical rib 16 is continuous from one end of thimble 10 to the other. Adjacent the base of rib 16, shell 20 is formed with a helical groove 26 which is preferably shallow in depth. Shallow groove 26 is likewise continuous from one end of thimble 10 to the other.

As shown more particularly in Fig. 3, thread or yarn 12 of relatively small diameter rests in groove 26 and is thereby guided through several turns around thimble 10 so that suitable tension may be

maintained on the thread. If the thread or yarn is of very large diameter, such as indicated in dotted lines at 30, it rests against the concave surface 18 of rib 16, being retained in position by overhanging lip 21. Thus, the continuous guiding means 15 comprising rib 16 and groove 26 maintain a tension on large diameter threads or yarns as well as on those of small diameter. Threads intermediate in diameter will rest partially in shallow groove 26 and partially against the concave inner surface of rib 16. Thimble 10 is thus adaptable to perform a thread guiding and tensioning function on threads of widely differing diameters.

The thimble may be made of any suitable material such as plastic, metal and so forth. Rib 16 and groove 26 may be formed in any desired manner, either by machining operations, or by being cast or otherwise formed in shell 29. The completed thimble forms a simple and effective device for preventing friction against a finger during knitting and crocheting operations, while still providing for maintaining tension on a thread or yarn which is guided along the thimble from one end to the other. As stated, the outer end of the thimble may be either closed or open without affecting the operation of the invention. Also, the shell may have a shape other than frusto-conical. The helical guiding means 15 may extend in either direction, and is shown as a "left-hand" thread only for the purpose of illustration.

While a specific embodiment of the invention has been shown and described in detail, to illustrate the application of the principles thereof, the invention may be otherwise embodied, without departing from such principles.

What is claimed is:

1. A thimble comprising a finger fitting shell, the external surface of said shell being formed with a thread or yarn guiding means continuous circumferentially and longitudinally of the shell and effective to guide the thread or yarn circumferentially and longitudinally of the thimble.

2. A thimble comprising a finger fitting shell having a closed outer end, the external surface of said shell being formed with a thread or yarn guiding and tensioning means continuous circumferentially and longitudinally of the shell and effective to guide the thread or yarn circumferentially and longitudinally of the thimble.

3. A thimble comprising a finger fitting shell, the external surface of said shell being formed with a helical thread or yarn guiding means effective to guide the thread or yarn substantially from one end of the thimble circumferentially and longitudinally to the other.

4. A thimble comprising a finger fitting shell having a closed outer end, the external surface of said shell being formed with a helical thread or yarn guiding means effective to guide thread or yarn of widely differing diameters substantially from one end of the thimble to the other.

5. A thimble comprising a finger fitting shell having a closed outer end, the external surface of said shell being formed with a projecting helical thread or yarn guiding and tensioning rib effective to guide thread or yarn of widely differing diameters from one end of the thimble to the other.

6. A thimble comprising a finger fitting shell having a closed outer end, the external surface of said shell being formed with a continuous thread or yarn guiding and tensioning means effective to guide thread or yarn of widely differing diameters from substantially one end of the thimble to the other, said means comprising a projecting helical rib and a helical groove adjacent the base of said rib.

10. 7. A thimble comprising a finger fitting shell having a closed outer end, the external surface of said shell being formed with a continuous thread or yarn guiding and tensioning means effective to guide thread or yarn of widely differing diameters from substantially one end of the thimble to the other, said means comprising a projecting transversely curved helical rib.

8. A thimble comprising a finger fitting shell having a closed outer end, the external surface of said shell being formed with a continuous thread or yarn guiding and tensioning means effective to guide thread or yarn of widely differing diameters from substantially one end of the thimble to the other, said means comprising a projecting transversely curved helical rib and a helical groove at the base of said rib adjacent the concave side thereof; said rib providing guiding means for relatively large diameter thread or yarn and said groove providing guiding means for relatively small diameter thread or yarn.

9. A thimble comprising a finger fitting shell, the external surface of said shell being formed with a continuous thread or yarn guiding and tensioning means effective to guide thread or yarn of widely differing diameters from substantially one end of the thimble to the other, said means comprising a projecting transversely curved helical rib; the transverse curve in said rib providing an overhanging yarn or thread retaining lip.

10. A thimble comprising a finger fitting shell, the external surface of said shell being formed with a continuous thread or yarn guiding and tensioning means effective to guide thread or yarn of widely differing diameters from substantially one end of the thimble to the other, said means comprising a projecting transversely curved helical rib and a shallow helical groove at the base of said rib adjacent the concave side thereof; the transverse curve in said rib providing an overhanging yarn or thread retaining lip; said rib providing guiding means for relatively large diameter thread or yarn and said groove providing guiding means for relatively small diameter thread or yarn.
